UNITED STATES PATENT OFFICE.

EDWIN LETTS OLIVER, OF OAKLAND, CALIFORNIA, ASSIGNOR OF ONE-HALF TO ARTHUR DE WINT FOOTE, OF GRASS VALLEY, CALIFORNIA.

APPARATUS FOR CYANID TREATMENT.

SPECIFICATION forming part of Letters Patent No. 784,120, dated March 7, 1905.

Application filed June 20, 1904. Serial No. 213,274.

To all whom it may concern:

Be it known that I, EDWIN LETTS OLIVER, a citizen of the United States, residing at Oakland, county of Alameda, State of California, have invented certain new and useful Improvements in Apparatus for the Cyanid Treatment of Gold and Silver Bearing Materials; and I do hereby declare the following to be a full, clear, and exact description of the same.

10 My invention relates to the treatment of ores, tailings, concentrates, and other materials by the cyanid process to obtain their gold and silver values, and particularly to that form of treatment in which the material, with the 15 addition of the cyanid or other solvents, is subjected to agitation in the presence of suitable electrodes.

The difficulty and expense of separating cyanid solutions from the ore or other material 20 prior to the extraction of the gold and silver from said solutions are well known and are especially marked with slimy ores or material, with which filtration or decantation is particularly slow and difficult. This has led to many 25 attempts to treat the material itself directly, the plates being placed in the agitator; but a serious difficulty in this has been the scouring of the plates. In order to get the material in contact with the plates, it has to be 30 agitated, and this, together with the fact of the use of material itself containing sand and other hard particles, has heretofore rendered such attempts practical failures, because of 35 said scouring.

35 The object of my invention is to overcome this difficulty of the scouring of the plates by providing an agitation of such character that the material will be kept in a continuous gentle circulation, by which it is carried into effective contact with plates without any tendency to scour them.

Another object is to provide a simple and effective means to automatically supply quicksilver to the plates while in use, thereby prolonging the period of their employment before taking them out to remove the gold and silver deposited upon them.

To these ends my invention consists in the novel arrangement, construction, and combi-

nation of the several parts of the apparatus, 50 which I shall hereinafter more fully describe.

Referring to the accompanying drawings, Figure 1 is a vertical section of my apparatus. Fig. 2 is a plan of same, some of the electrodes being omitted. Fig. 3 is an enlarged top view 55 detail showing the mounting of the electrodes and their electrical connections. Fig. 4 is an enlarged detail showing in cross-sectional elevation the electrode connections. Fig. 5 is an enlarged view showing electrode supports and 60 connections. Fig. 6 is a detail showing the connection for the anode-plates E.

A is a tank.

B is the discharge from the bottom of the tank, said discharge being controlled by a 65 gate b.

Within the tank, at its bottom, is bolted a casting d, having openings d' in its sides. This casting receives a pipe D, rising in the tank to its upper portion. Through the open-sided 70 casting d the lower end of the pipe communicates with the lower portion of the tank. The top of pipe D is open.

C is an air-pipe leading from the compressor. (Unnecessary to show.) The air-pipe 75 enters through the bottom discharge of the tank and rises into the pipe D.

In the upper part of the tank are suitably supported the electrodes E and F. These alternate, as usual, the electrodes E being the anodes 80 and made of iron plates or other suitable material and the electrodes F being the cathodes and made of copper plates which are coated with quicksilver, thereby making them amalgamated plates. These electrodes are in great 85 number to give extensive surface. They are disposed vertically and close together. Any suitable means may be employed to hold them. A simple construction is that here shown.

G represents blocks secured to the tank- 90 wall. These support wooden strips H, on which rest edgewise the boards I, having spaced grooves or guides in their sides, in which the plates are held, the bottoms of the plates resting on the strips H. The electrical 95 connection with the anode-plates E is formed by iron bars J on top of the boards I. With these bars the anode-plates E are connected

by the angle-iron brackets *e*, and said bars at one end are turned up and are connected with the positive wires *j*. The electrical connection with the cathode or amalgamated copper plates *F* is made as follows: Supported upon the iron bars *J* are insulating-strips *K* of suitable material, such as rubber. Upon these strips *K* are supported the open-topped troughs *L*, flanked by insulating-strips *k*. In the bottom of each trough *L* is laid a copper bar *M*, one end of which is upturned and has connected with it the negative wire *m*. In each trough is a body of quicksilver, (represented by *N*.) To each cathode *F* is riveted a copper lug *O*, having an arm *o* extending over the edge of the trough *L* and immersed in the quicksilver therein. This construction in addition to forming an effective electrical connection has the further important function of automatically supplying the copper plates with quicksilver. These plates, as before stated, are coated with quicksilver; but as the gold and silver are deposited upon them and when it would otherwise be necessary to take them out to remove the deposits they may be allowed to remain longer if they are supplied with fresh quicksilver. The quicksilver creeps along the arms *o* and over the lugs *O* and spreads upon the plates *F*, thereby supplying the necessary amalgam to the plates and lengthening the period of their use before they have to be taken out to remove the deposits.

The operation is as follows: The material to be treated and the cyanid or other solvent solutions fill the tank *A* above the level of the pipe *D*. Air being turned on through pipe *C*, the effect is to lighten the column of the mixture in pipe *D*, whereupon the pressure outside the pipe causes a continuous circulation of the mixture upwardly through pipe *D* and downwardly between and past the electrodes and to the bottom of the tank and into the pipe *D* again. By the electric current the gold and silver are deposited on the amalgamated copper plates *F*. This agitation and circulation of the mixture can be regulated by the air to be as gentle as desired, and though efficient contact with the plates *F* is made there is no scouring of said plates.

Having thus described my invention, what I claim as new, and desire to secure by Letters Patent, is—

1. An apparatus for the cyanid treatment of gold and silver bearing materials, comprising a tank; an open-topped pipe rising within and opening directly into the upper portion of said tank, the lower end of said pipe having communication with the lower portion of the tank; a connection from a source of compressed air communicating with the lower end of the pipe; anode and cathode plates within the tank; and suitable electrical connections to said plates.

2. An apparatus for the cyanid treatment of gold and silver bearing material, comprising

ing a tank; an open-topped pipe rising within and opening directly into the upper portion of said tank, the lower end of said pipe having communication with the lower portion of the tank; a connection from a source of compressed air communicating with the lower end of the pipe; electrodes within the tank, the cathode-electrodes being amalgamated plates; and suitable electrical connections to the electrodes.

3. An apparatus for the cyanid treatment of gold and silver bearing materials, comprising a tank; an open-topped pipe rising within and opening directly into the upper portion of said tank, the lower end of said pipe having communication with the lower portion of the tank; a connection from a source of compressed air communicating with the lower end of the pipe; amalgamated plates in said tank; and means for electrolytically depositing the gold and silver upon said plates.

4. An apparatus for the cyanid treatment of gold and silver bearing materials, comprising a tank; an open-topped pipe rising within and opening directly into the upper portion of said tank, the lower end of said pipe having communication with the lower portion of the tank; a connection from a source of compressed air communicating with the lower end of the pipe; anode and cathode plates within the tank; a suitable electrical connection with the anode-plates; and an electrical connection with the cathode-plates comprising troughs with quicksilver, and metallic arms extending from the cathode-plates into the quicksilver in the troughs, said arms being unobstructed to the creeping passage of the quicksilver over them, whereby said plates are amalgamated.

5. An apparatus for the cyanid treatment of gold and silver bearing materials, comprising a tank; an open-topped pipe rising within and opening directly into the upper portion of said tank, the lower end of said pipe having communication with the lower portion of the tank; a connection from a source of compressed air communicating with the lower end of the pipe; electrodes within the tank, the cathode-electrodes being amalgamated plates; a suitable electrical connection with the anode-plates; and an electrical connection with the cathode-plates comprising troughs with quicksilver, and metallic arms extending from the cathode-plates into the quicksilver in the troughs, said arms being unobstructed to the creeping passage of the quicksilver over them, whereby said amalgamated plates are replenished with quicksilver.

6. In an apparatus for the cyanid treatment of gold and silver bearing materials, and in combination with amalgamated plates therein, the troughs containing quicksilver, and the metallic arms from said plates dipped in the quicksilver, said arms being unobstructed to the creeping passage of the quicksilver over them,

whereby the plates are replenished with quicksilver.

7. In an apparatus for the cyanid treatment of gold and silver bearing materials, and in combination with amalgamated plates therein, the troughs containing quicksilver, the metallic arms from said plates dipped in the quicksilver, said arms being unobstructed to the creeping passage of the quicksilver over them, whereby the plates are replenished with

quicksilver and the conductors in the quicksilver with which the electrical connection is made.

In witness whereof I have hereunto set my hand.

EDWIN LETTS OLIVER.
